AUTOMOBILE LAMP

Clifford C. Voss, Clawson, Mich., assignor to Chrysler Corporation, Highland Park, Mich., a corporation of Delaware

Application June 11, 1956, Serial No. 41,868

Term of patent 7 years

(Cl. D48—32)

Fig. 1 is a side elevational view of an automobile lamp showing my new design;

Fig. 2 is a front elevational view thereof; and

Figs. 3, 4 and 5 are sectional views taken on the lines 3—3, 4—4 and 5—5, respectively, of Fig. 2.

I claim:

The ornamental design for an automobile lamp, substantially as shown.
